ARTIFICIAL ASTERIA

Ralph S. Mukai, New York, N. Y.

Application February 3, 1948, Serial No. 5,942

2 Claims. (Cl. 63—32)

1

This invention relates to artificial asteriae and to means for artificially producing asterism in gem stones.

In using the expression "gem stones" I do not limit myself to the commonly accepted meaning, that is, a natural stone of large intrinsic value; although my invention will probably be practiced most frequently with synthetic stones such as synthetic rubies, sapphires, spinel, alexandrites, and the like, it may be employed also on genuine stones or on "paste" or artificial stones.

The rarity and value of genuine asteriae, such as star rubies and sapphires, has encouraged the lapidary and the gem stone synthesizer to seek means for artificially producing asterism. It has been proposed, for example, to create asterism by cementing a specially treated reflective backing to the rear base of a synthetic cabochon-cut stone or by grinding a concavity in the back of such a stone and actually cutting the outline of a star into the rear wall of the stone. None of these attempts has been well received; the resulting asterism is flat and "dead," and is so patently and recognizably artificial that people generally are reluctant to wear stones which have been so treated.

My process, which I have derived after extensive research and experimentation, may be employed to produce asterism in any hard, transparent or translucent material which is capable of reflecting light, without resorting to "doublets," as compound stones are known, and without noticeably cutting or otherwise disfiguring the stone itself. A genuine stone may be asterized by my method without danger of damaging or disfiguring it. Owners of genuine cabochon rubies, sapphires, or other stones may at small cost increase the intrinsic value of the gem by having them asteriated.

My invention may be practiced on any cabochon-cut stone, natural, synthetic, or artificial, regardless of the size or shape; and will produce a star which is visible not only from above, but from all sides of the stone.

It is an object of the invention therefore to provide an improved method of artificially producing asterism.

It is a still further object of the invention to provide means for stimulating the natural asterism of certain gem stones, without disfiguring the stone or requiring extensive grinding, polishing, or cutting operations.

Other features and advantages will hereinafter appear.

In the accompanying drawings:

2

Fig. 1 is a side elevation of a cabochon-cut stone, and

Fig. 2 is a base plan view of the same after the asterism treatment has been applied thereto.

Figs. 3 and 4 are respectively a side elevation and a base plan view of a double cabochon stone treated in slightly different manner to produce asterism.

Fig. 5 is a side elevation, partly in section, and enlarged to show details of one means of practicing my invention.

Fig. 6 is a partial base plan view of a stone treated in a third manner to produce asterism, and

Fig. 7 is a perspective of a stone treated in any of the above enumerated ways and indicating the appearance of the asteria therein.

Referring now to Fig. 1 the cabochon-cut stone 10 has a plane base 11. The stone and base may be finely ground and polished; that is, there is usually no need for further grinding or polishing after the asterism-producing step. The stone 10 may be set in cement 12 on a dop stick 14 for support. Then, using means such as the cylindrical iron bar 15 suitably held in a rotating chuck 16 and fine gem-polishing dust, the base 11 is given a great multiplicity of minute, sharp, shallow cuts or grooves over the three intersecting areas 17. Three areas of engraving intersecting as shown in Fig. 2 will produce a six-rayed star. This is the desired treatment because it simulates the asterism of a natural gem. The individual cuts or engravings are short and may be considered to be substantially parallel one with the other. The individual cuts should extend at an angle, preferably a right angle, with respect to the radii of the back of the stone.

In the Fig. 3 embodiment the stone 20 has a double cabochon-cut in that the base 21 is also convex. A somewhat different pattern of engraving has been employed, as will be noted; the respective engraved areas 17' are wider at the girdle than at the center of the base. Preferably said areas are not truly triangular in that there is no clearly defined apex. The asterism thus produced is also characterized by a bright center and well-defined luminous rays. In the Fig. 6 embodiment the entire base is lightly engraved.

The resulting individual cuts are arcuate, intersecting the radii of the base. These individual lines of engraving are not necessarily concentric; in fact a somewhat irregular pattern often produces superior luminosity in the "star." It will be understood that Fig. 6 shows a portion only,

of the stone 30, and that but one sector 17" thereof has been treated.

The engravings or markings of the forms of Figs. 3 and 6 are perhaps best accomplished by holding the rod 15 at an angle as shown in dot-dash lines of Fig. 5. A vibrating tool, rather than a rotating tool, may be employed, and other mechanical expedients will suggest themselves to the skilled lapidary.

It should be understood that the respective figures exaggerate the prominence of the engraved areas. In fact the individual lines of engraving are exceedingly fine and when the stone is viewed under indirect light are hardly discernible.

The asterism is produced by the reflection of rays of direct light from the multitudinous facets or side walls of the engraved lines. A feature of asteriae produced by my method is that the stars thereof seem to move within the stone as the stone and light source are moved relative to each other. The star therefore has realism which has not, to my knowledge, been obtained by any other method. Fig. 7, illustrates the appearance of the stone when the stone is viewed from above, under direct light.

Thus, among others, the several objects of the invention as afore noted are achieved. Obviously numerous changes in construction and rearrangement of the parts might be resorted to without departing from the spirit of the invention as defined by the claims.

I claim:

1. An artificial asteria in a body of hard transparent material cut en cabochon to form a rear surface comprising a plurality of relatively narrow radially extending areas on said rear surface substantially free from short minute

separate grooves parallel to the radii of said rear surface, a multiplicity of short closely spaced minute separate grooves formed in said relatively narrow radially extending areas, said short grooves being solely substantially perpendicular to the radii of said rear surface and to the long dimension of said radially extending areas, and a plurality of relatively broad radially extending areas on said rear surface interposed between and separating said relatively narrow grooved areas.

- 10 2. An artificial asteria in a body of hard transparent material cut en cabochon to form a rear surface comprising a plurality of relatively narrow radially extending areas on said rear surface substantially free from short minute separate grooves parallel to the radii of said rear surface, a multiplicity of short closely spaced minute separate grooves formed in said relatively narrow radially extending areas, said short grooves being solely substantially perpendicular to the radii of said rear surface and to the long dimension of said radially extending areas, and a plurality of relatively broad radially extending 20 areas on said rear surface of said gem substantially free from all short minute grooves and separating said relatively narrow grooved areas.
